UNITED STATES PATENT OFFICE.

CHARLES A. WYMAN, OF AUBURN, WASHINGTON.

MOLE TRAP.

Application filed June 20, 1925. Serial No. 38,403.

This invention relates to mole traps; and its object is to provide a trap of this character which will be of simple and inexpensive construction, convenient to set, and efficient in operation.

The invention consists in the novel construction, arrangement and combination of parts hereinafter described and claimed.

In the accompanying drawing,

Figure 1 is a side elevation of a mole trap embodying my improvements, the trap being illustrated in its set position; Fig. 2 is a view of the same, partly in front elevation and partly in vertical section, said section being on the line 2—2 of Fig. 1; Fig. 3 is a sectional view taken substantially on line 3—3 of Fig. 2; and Fig. 4 is a rear elevation of the upper portion of the trap showing the plunger held in its safety position.

The frame of the trap consists of a vertical standard 5, preferably of an oblong rectangular shape, having rigidly secured to its lower end two pairs of legs 6 and 6¹. As shown, the complementary legs of each pair thereof are formed integral with horizontal bar elements 7 and 7¹, respectively, and are secured to the front and rear surfaces of the standard 5 by means of bolts 8 passing through said bar elements. The legs, moreover, are bent as at 9 to provide offset lower portions 10 which are substantially parallel with the standard 5. The off-setting of the legs afford space between the legs at each end of the trap, see Figs. 1 and 3, to extend into the earth at opposite sides of a mole runway which is indicated by A. The trap is provided with a plunger of substantially the shape of an inverted letter U, having a horizontal rod element 11 and pointed side elements 12 which extend downwardly through guides 13 secured to the opposite sides of the standard. Said plunger is also guided in a way for the plunger element 11, said way being provided between the front surface of the standard and a guide rod 14 secured to the latter.

15 represents a slot provided in the standard to receive the plunger element 11 whereby the plunger is temporarily held in its safety position when setting or regulating the trap.

16 represents an arm pivotally connected as by a screw 17 to said standard and adapted to be swung into the position in which it is shown in Fig. 4 to prevent the accidental displacement of the plunger from the slot 15.

Secured as by means of a screw 18 to the upper portion of the standard is one arm of a sear spring 19 having its striking arm 20 extended through a guide slot 21 of the standard into engageable relation with the plunger at or about the midlength of its horizontal element 11.

The spring arm 20 is releasably held in operative position upon the shoulder 22 of a lever 23 which is fulcrumed to a pin or screw 24 secured to the standard at one side of its slot 21.

The free end of the lever 23 is engaged by a trip-arm 25 fulcrumed to a staple 26 at one side of the standard. Said trip-arm is provided, preferably at its free end, with a finger 25¹ which extends downwardly into engageable relation with the upwardly directed arm 27 of a lever which is fulcrumed at 28, the other arm 29 of this lever extending downwardly into the runway A when in use.

The lever 27—29 constitutes the trap trigger and is guided by an attachment 30 of the standard for swinging movements transversely of the standard, or longitudinally of the runway.

To set the trap, the operator grasps the standard 5 in one hand and with his other hand raises the spring's striking arm 20 by means of the plunger whose element 11 he lodges in the groove 15 and within which said element is temporarily held in its safety position as represented in Fig. 4 by means of the arm 16.

Such positioning of the plunger elements is also indicated by dotted lines 11¹ and 12¹ in Fig. 3. The lever 23 is then moved from its dotted line position 23¹ into its full line position in Fig. 2, its free end being engaged by the trip arm 25 which, in turn, is held in its Fig. 2 position by means of the trigger arm 27 engaging the arm finger 25¹. A section of earth is then removed from above the mole runway A as indicated for example by B between dotted lines C in Fig. 1.

The trap is secured in the position in which it is illustrated in Figs. 1, 2 and 3 to have the legs 6 and 6¹, respectively, engage in the ground at opposite sides of the runway and the trigger arm 29 extend into the latter. In case bait is to be used on the trigger arm, it is necessary to remove the earth above the runway A as, for example, the section indicated by B between dotted lines C in Fig. 1. Where such earth is re-

5 moved loose earth is employed to close, as indicated by D in Fig. 2, the runway below the opening and also the opening itself in place of the section B. The closing of the runway as above explained is of advantage even though no bait be employed. With the trap thus arranged the plunger is withdrawn from the groove 15 and pushed down to have the plunger points engaged in the 10 ground and the rod element 11 of the plunger located in spaced relation below the position in which the striking arm 20 of the spring is held by means of the lever shoulder 22.

15 A mole in traveling through the runway in either direction encounters the trigger arm 29, or otherwise disturbs it, in a manner to cause the other arm 27 of the trigger to become disengaged from the finger 25¹ of the trip arm 25; whereupon the lever 23 is thrust aside, as at 23¹, by the power of the spring 19, thereby permitting the striking arm 20 to violently engage the plunger to start the same and follow it so that the plunger is 20 driven downwardly with such force as to impale the mole upon one or the other of the plunger prongs.

25 What I claim, is,—

1. The combination with a trap frame 30 having a slot, a plunger mounted for relative vertical movements to said frame, a sear spring for imparting downward movement to said plunger, said spring having one of its arms secured to the frame and its other 35 arm extend through said slot into striking relation with the plunger, and a trigger fulcrummed to the frame, of connections between

the trigger and the spring for releasably retaining the striking arm of latter in operative relation with respect to the plunger, 40 said connections including a lever provided with a shoulder which is engageable with the spring for supporting the striking arm thereof and a trip arm controlled by the trigger for releasably retaining the lever in 45 engaged relation with the spring.

2. A mole trap comprising a vertical standard and two pairs of spaced apart supporting legs therefor, said standard being provided with a vertical slot, a plunger of 50 substantially the shape of an inverted letter U connected for vertical movements to the standard, a spring connected to said standard and having a striking arm extending through said slot, a lever pivotally connected 55 to the standard, said lever having a shoulder engaging the spring for normally supporting said striking arm and permit movement of the plunger independently of the spring, a trigger pivotally connected intermediate its length to the standard, and a trip arm engageable with the trigger and also with said lever to releasably hold the latter until the trip arm is disengaged with respect to the trigger. 60

3. A mole trap as defined in claim 2 wherein the standard is formed with a recess providing a seat for supporting the plunger in its safety position, and means for releasably securing the plunger within said 65 recess.

Signed at Seattle, Washington, this 29th day of May 1925.

CHARLES A. WYMAN.
